UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

ELECTRIC CONTROLLING DEVICE.

Original application filed July 22, 1918, Serial No. 246,219. Divided and this application filed April 18, 1923. Serial No. 632,332.

This invention relates to electric controlling devices, and more especially to a reversing switch.

One object of the present invention is to provide an improved current controlling mechanism. Another object of the present invention is to provide an improved reversing switch which is composed of but few parts which are easily manufactured, easily assembled, and which may be readily disassembled. Still another object of the present invention is to provide an improved construction wherein when the parts of the switch are assembled they are locked in assembled relation and wherein certainty and adequacy of contact between the stationary and movable contact elements is assured. These and other objects and advantages of my improved construction will, however, hereinafter more fully appear.

In the accompanying drawings I have shown for purposes of illustration one form which my invention may assume in practice.

In these drawings,—

Fig. 1 is a central vertical section of the illustrative form of my improved current controlling mechanism.

Fig. 2 is a perspective view of certain parts of the switch in disassembled relation.

Upon a plate of insulating material 1, there is arranged a cruciform insulating plate 2. Mounted upon the plate 1 in spaced relation to each other and equi-angularly spaced about a circle are a series of stationary contact elements, generally indicated by 3, each of which is provided with an enlarged head or contact member proper 4 and a bolt-like portion 5. These bolt-like portions extend through holes 6 in the plate 1 and cooperate with nuts 7 in securing the contacts on the plate 1. The nuts 7 together with other nuts 8 constitute holding means between which the wires of the circuit to be reversed are connected. It will be noted that the contacts 4 lie between the arms of the cruciform member 2. Cooperating with the stationary contacts 4 is a movable switch element which comprises a disc 10 provided with a transverse slot 11 between a pair of lugs 12 formed on the upper side thereof, said disc being rotatably mounted in a bearing formed by an annular flange 13 on an insulating guard plate 14 which is secured to the plate 1 as by bolts 15. The disc 10 carries on its face op-

posite the lugs 12 a pair of segmental contact plates 16 which engage the contact members 4 and serve to connect them in pairs. The contact plates 16 are connected to the disc 10 by means of lugs 17 which project from the rear face of the plates and loosely engage 60 sockets (see Fig. 1) in the disc 10. As a result, the plates 16 are free to partake of oscillation and will always tilt in such manner as to rest solidly upon the contacts 4, should the latter for any reason happen to lie with their 65 tops in slightly different planes. For the purpose of rotating the disc 10 a shaft 18, to whose inner end the hollow hub 19 of a T-shaped head 20 is secured, is provided and this T-shaped head is adapted to be loosely received in the recess between the lugs 12 on the back of the disc 10. A shoulder 21 on an element (shown broken away) prevents the head 20 from moving bodily away from the disc 10 and a spring 22 is loosely interposed 75 between the disc 10 and the end of the shaft 18 and located within the hollow hub 19 for the purpose of resiliently pressing the plate 10 and its contacts 16 toward the stationary contacts 4. The element shown broken away 80 and the plate 1 may be held in spaced relation by bolts provided with spacing sleeves. It is obviously immaterial whether it is the plate which supports the said element, or whether the said element supports the plate 1. In the 85 particular embodiment which I have devised the plate 1 is supported from the other element. It will be observed that the bolts 15 hold the member 14 to the bottom plate 1 and that the members 1 and 14 form an open 90 ended insulating casing for the stationary and moving contacts, which casing has its open end closed by the rotatable insulating contact carrying member 10. It will be observed, moreover, that when the plate 1 is 95 detached and moved away from the element which carries the stationary shoulder 21, the entire reverse switch can be readily disassembled by simply removing the bolts 15. The member 2 is easily replaceable and minimizes burning of the plate 1.

This application is a division of my application Serial No. 246,219, filed July 22, 1918, on which Letters Patent 1,556,826 have issued under date of October 13, 1925.

While I have in this application specifically described one form which my invention may assume in practice, it will be understood

2
that this form is shown for purposes of illustration only and that the invention may be modified and embodied in various other forms without departing from its spirit or the scope 5 of the appended claims.

What I claim as new and desire to secure by Letters Patent is:

1. In a switch, a plurality of flat stationary contacts, a plurality of separate flat 10 movable contacts adapted to bear always uniformly on said other contacts, a rotatable plate by which said movable contacts are loosely guided, an operating member for actuating said plate and connected to the latter, and resilient means acting on said plate for forcing said contacts together.

2. In a switch, a plurality of flat stationary contacts, a plurality of separate flat movable contacts adapted to bear always uniformly 20 on said other contacts, a rotatable plate by which said movable contacts are loosely guided, an operating member for actuating said plate and having a longitudinally 25 slidable interlocking connection with the latter, and a spring acting between said plate and operating member for forcing said contacts together.

3. In a switch, a plurality of flat stationary contacts, a plurality of separate flat 30 movable contacts adapted to bear always uniformly on said other contacts, a rotatable plate for loosely guiding said movable contacts, said plate engaging each movable contact only adjacent the center thereof, an operating member for actuating said plate, and a spring acting between said plate and operating member for forcing said contacts together.

4. In a switch, a plurality of flat stationary 40 contacts, a plurality of separate flat movable contacts adapted to bear always uniformly on said other contacts, a rotatable plate for loosely guiding said movable contacts, said plate engaging each movable contact only 45 adjacent the center thereof, an operating member for actuating said plate and having a longitudinally slidable interlocking connection with the latter, and a spring acting between said plate and operating member 50 for forcing said contacts together.

5. In an apparatus of the character described, a switch comprising, in combination, a plurality of stationary contact members, a disk having contact members cooperating 55 with said first named contact members, an insulating guard in which said disk is rotatably mounted, a shaft loosely connected with said disk for rotating the same, and a spring interposed between said disk and the end of 60 said shaft for pressing the contacts on the former into engagement with said contact members.

6. In an apparatus of the character described, a switch comprising in combination, 65 a plurality of stationary contact members, an

insulating plate having portions extending between said members, a disk having contact plates adapted to cooperate simultaneously with a plurality of said contact members, an insulating guard in which said disk is rotatably mounted, a shaft loosely connected with said disk for rotating the same, and a spring interposed between said disk and the end of said shaft for pressing the former toward said contact members.

7. In an apparatus of the character described, a switch comprising, in combination, a plurality of stationary contact members, a disk carrying on its face a plurality of loosely mounted contact plates adapted to cooperate simultaneously with a plurality of said contact members, a shaft loosely connected with said disk for rotating the same, and a spring interposed between said shaft and disk for pressing the latter toward said contact members.

8. In a switch, an insulating casing having an open ended chamber, a plurality of flat stationary contacts disposed in said chamber, a plurality of separate flat movable contacts adapted to always bear uniformly on said other contacts, a rotatable insulating member closing the open end of said chamber and having recesses for loosely guiding said movable contacts, an operating member connected to said closure member for actuating the latter, and resilient means acting on said closure member for forcing said contacts together.

9. In a switch, an insulating casing having an open ended chamber, a plurality of flat stationary contacts disposed in said chamber, a plurality of separate flat movable contacts adapted to bear always uniformly on said other contacts, a rotatable insulating member for closing the open end of said chamber and having means for loosely guiding said movable contacts, said latter contacts having centrally located dowel pins projecting within said recesses, an operating member for actuating said closure member and having a longitudinally slidable interlocking connection with the latter, and a spring acting between said operating member and closure member for forcing said contacts together.

10. In a switch, an insulating casing having an open ended chamber, a plurality of radially spaced flat stationary contacts disposed in said chamber, an insulating member having portions disposed between said contacts, a plurality of separate flat movable contacts adapted to always bear uniformly on said other contacts, a rotatable insulating member for closing the open end of said chamber and having recesses for loosely engaging said movable contacts to guide the same, an operating member for actuating said closure member and having a longitudinally slidable interlocking connection with the lat-

ter, and a spring acting between said operating member and said closure member for forcing said contacts together.

11. In a switch, an insulating casing having an open ended chamber, a plurality of flat stationary contacts disposed in said chamber, a plurality of separate flat movable contacts adapted to bear always uniformly upon said other contacts, a rotatable insulating member for closing the open end of said chamber and having recesses for loosely engaging said movable contacts to guide the same, an operating member for actuating said closure member and having a longitudinally 15 slidable interlocking connection with the latter, and a spring acting between said operating member and said closure member for forcing said contacts together.

12. In a switch, an insulating casing having an open ended chamber, a plurality of flat stationary contacts disposed in said chamber, a plurality of separate flat movable contacts adapted to always bear uniformly on said other contacts, a rotatable insulating member for closing the open end of said chamber and having recesses for loosely engaging said movable contacts to guide the same, said member having a transverse slot formed in the upper surface thereof, an operating member for actuating said closure member having a transverse portion projecting within said slot, said transverse portion and slot forming a longitudinally slidable interlocking connection between said operating 25 member and closure member, and a spring acting between said operating member and closure member for forcing said contacts together.

13. In a switch, an insulating casing having a chamber, stationary contacts disposed within said chamber, separate movable contacts adapted to bear always uniformly on said other contacts, a rotatable insulating member for closing said chamber and with which said movable contacts are engageable, an operating member for actuating said closure member and having a longitudinally slidable interlocking connection with said closure member, and a spring acting between said closure member and operating member for forcing said contacts together.

14. In a switch, an insulating casing having an open ended chamber, a plurality of flat stationary radially spaced contacts disposed in said chamber, an insulating member having portions projecting between said contacts, a plurality of flat movable contacts adapted to always bear uniformly on said other contacts, said movable contacts having projecting centrally located lugs formed thereon, an insulating member for closing the open end of said chamber and having recesses within which said lugs project for loosely engaging said movable contacts to guide the same, said closure member having a transverse slot formed therein, an operating member for actuating said closure member having a transverse portion projecting within said slot, said transverse portion and slot forming a sliding interlocking connection between said closure member and operating member, and a spring acting between said operating member and closure member for forcing said contacts together.

In testimony whereof I affix my signature.
CHARLES W. WYMAN.
